(57) **CLAIM**

The ornamental design for a housing for electric device, as shown and described.

DESCRIPTION

FIG. 1 is a perspective view of a first embodiment of a housing for electric device showing our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a partially enlarged perspective view thereof along the lines 7-7 and 7'-7' of FIG. 1;

FIG. 8 is a partially enlarged rear view thereof along the lines 8-8 and 8'-8' of FIG. 2;

FIG. 9 is a partially enlarged perspective view thereof along the lines 9-9 and 9'-9' of FIG. 1; and

FIG. 10 is a partially enlarged left side elevational view thereof along the lines 10-10 of FIG. 3.

FIG. 11 is a perspective view of a second embodiment of a housing for electric device showing our new design;

FIG. 12 is a rear elevational view thereof;

FIG. 13 is a left side elevational view thereof;

FIG. 14 is a right side elevational view thereof;

FIG. 15 is a top plan view thereof; and

FIG. 16 is a bottom plan view thereof.

FIG. 17 is a partially enlarged perspective view thereof along the lines 17-17 and 17'-17' of FIG. 11;

FIG. 18 is a partially enlarged rear view thereof along the lines 18-18 and 18'-18' of FIG. 12;

FIG. 19 is a partially enlarged left side elevational view thereof along the lines 19-19 and 19'-19' of FIG. 11; and, FIG. 20 is a partially enlarged left side elevational view thereof along the lines 20-20 of FIG. 13.

The broken lines shown represent portions of the housing for electric device that form no part of the claimed design. Where the dot-dash broken lines abut the shaded surface it is understood that those broken lines represent an unclaimed boundary between claimed and unclaimed surfaces. None of the broken lines form any part of the claimed design.
